UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

PULL-SWITCH SOCKET.

Application filed July 26, 1920. Serial No. 399,080.

My invention relates to electric circuit controllers, and more specifically to pull switch sockets.

One of the objects of my invention is to provide an improved pull switch socket which will be suitable for heavy duty, which will be efficient and durable in operation, simple in construction and cheap to manufacture.

10 A further object is to provide a snap switch mechanism which has high current carrying and circuit breaking capacity, and which is sufficiently small and compact to admit of its being placed in the casing of the usual lamp socket.

15 A further object is to provide a switch mechanism which can be used in a socket and which will give a quick double break and have a high capacity, without requiring that a hard pull be given to the flexible cord or chain to operate it.

20 Further objects will appear from the detailed description to follow, and from the appended claims.

25 In the drawings, in which an embodiment of my invention is shown;

Fig. 1 is a side elevation of the interior of a pull switch socket removed from the enclosing casing;

30 Fig. 2 is a plan view of the construction shown in Fig. 1;

Fig. 3 is a section on the line 3—3 of Fig. 1;

Fig. 4 is a bottom plan view of the construction shown in Fig. 1;

Fig. 5 is a section on the line 5—5 of Fig. 2;

Fig. 6 is a section on the line 6—6 of Figs. 2 and 3;

40 Fig. 7 is a section on the line 7—7 of Fig. 2;

Fig. 8 is a detail plan view of part of the switch mechanism;

Fig. 9 is a section on the line 9—9 of Fig. 8;

Fig. 10 is a section on the line 10—10 of Fig. 3;

Fig. 11 is a detail view of part of the switch construction;

50 Fig. 12 is a side elevation of the switch base;

Fig. 13 is a fragmentary view of part of the switch mechanism;

Fig. 14 is a side elevation of a ratchet member, and

Fig. 15 is a plan view of the ratchet member shown in Fig. 14.

The construction shown in the drawings comprises in a general way, a switch socket comprising an insulating base 20, shell and center contacts 21 and 22 respectively, supported by the insulating base, wiring terminals 23 and 24 for the contacts 21 and 22 respectively, and switch mechanism 25 for controlling the circuit between the wiring terminal 24 and the center contact 22.

The entire construction shown is enclosed in an ornamental sheet metal housing (not shown), an insulating sleeve or cup 26 being provided around the threaded shell contact 21, to insulate it from this housing. The insulating base 20 is suitably recessed to provide room for the switch mechanism 25 and associated parts.

The threaded shell contact is always electrically connected with the wiring terminal 23 by means of a screw 27, the head of which engages the flange 28 of the threaded shell contact (Fig. 4) and the upper end of which is screwed into the binding plate 28^a 80 of the wiring terminal 23 (Fig. 2).

As stated above, the switch mechanism 25 controls the circuit between the wiring terminal 24 and the center contact 22. This circuit is broken between the two spring contact fingers 29 and 30 (Fig. 7), the spring contact finger 29 being always electrically connected with the center contact 22 by means of the screw 31, and the spring contact finger 30 being always electrically connected with the wiring terminal 24 by means of a screw 32.

The screws 27, 31 and 32, not only serve to electrically connect certain parts, but also serve to hold certain parts in place on the insulating base. Thus, the screw 27 holds the binding plate 28 in place, and also assists in holding the threaded shell contact in place (Figs. 2 and 4). The head of the screw 31 engages underneath the center contact 22, and its upper end extends through an opening in the base of the spring contact finger 29 (Fig. 7) and is threaded into a nut 33, so that this screw holds the center contact in place, and also the spring contact finger 29. The head of the screw 32 engages underneath the base of the spring contact finger 30 (Fig. 7) and its upper end is threaded into the binding plate 34 of the wiring terminal 24, so that this screw 32 110

holds the spring contact finger 30 and the binding plate 34 in place on the insulating base.

The switch mechanism 25 which controls the circuit between the two spring contact fingers 29 and 30 comprises a U-shaped pivoted switch arm 35, which may be a sheet metal stamping, a pull chain 36, a ratchet mechanism 37, actuated by said pull chain, whereby an intermittent rotary movement is obtained, and switch-throwing mechanism 38 actuated by said ratchet mechanism, whereby the intermittent rotary motion is converted into alternate up and down snap oscillation of the switch arm 35.

The ratchet mechanism 37 comprises a driven ratchet member 39 (shown in detail in Figs. 14 and 15) and a driving ratchet member 40, which is oscillated by the pull chain 36. The driven ratchet member 39 may be a sheet metal stamping, having a pair of wings 41, which are engaged and driven by the ratchet teeth 42 of the driving ratchet member 40. For operating the switch-throwing mechanism 38, the driven ratchet member 41 is provided with a crank pin or cam portion 43 (Figs. 9 and 15) which operates in an elongated opening 44, in the swinging spring-shifting member 45 of the switch-throwing mechanism 38.

For positioning the driven ratchet member 39 at the end of its intermittent movement and for preventing it from returning as the driving member is returned, this driven member 39 is provided with a rectangular positioning portion 46, which snaps endwise into a rectangular depression 47 (Fig. 12) in the switch frame 48, this being effected by the action of the combined torsion and compression spring 49 (Figs. 2 and 6). As will be hereinafter explained, this spring 49 serves to return the pull chain 36 after it has been pulled down, and as just stated it also serves to urge the switch mechanism to the left as shown in Fig. 6 so that when the positioning portion 46 of the driven ratchet member is in registration with the rectangular depression 47 in the switch frame 48 the positioning member 46 will be caused to snap into the depression to position the driven ratchet member and to prevent it from returning as the driving ratchet member is returned by the torsion spring 49.

For guiding the end 50 of the swinging member 45, the switch frame 48 is provided with an upstanding guide or abutment 51 (Figs. 9 and 12) along which the end 50 slides as it is moved up and down by the action of the cam member 43. The other end 52 of this member 45 extends through and works back and forth in an opening in the cross-bar 53 of the switch arm 35 (Figs. 8 and 9).

In order to give a snap action to the switch mechanism, a coil compression spring 54 is provided, which surrounds the swinging member 38, one end of this spring bearing on the cross piece 53 of the switch arm, and the other bearing against the shoulder 70 55 of the swinging member 38 and forcing it back against the abutment 51 (Figs. 8 and 9).

For connecting the pull chain 36 to the driving ratchet member 40, the pull chain 75 is secured to a chain rail 56, which chain rail is in turn secured to the ratchet member 40 by means of an eyelet 57 (Fig. 6). As the driving ratchet member 40 is a live part it must be insulated from the pull chain 36, 80 and for this purpose a pair of insulating fibre washers or discs 58 and 59 are provided, between which the chain rail 56 is clamped by means of the eyelet 57 previously referred to.

For pivotally mounting the oscillating switch arm 35, the oscillating chain rail 56, and the oscillating driving ratchet member 40, and for rotatably mounting the driven ratchet member 39, a switch shaft or spindle 90 60 is provided, one end of which is supported in an opening 61, (Fig. 12) in the switch frame 48, and the other end of which is mounted in an opening 62 in the shaft bracket 63 (Figs. 6 and 10). This shaft or 95 spindle 60 extends through the eyelet 57, through suitable holes in the driven ratchet member 39, and also through suitable holes in the arms 64 and 65 of the oscillating switch arm 35. This shaft also extends 100 through the elongated opening 44 in the swinging member 45, this opening 44 being enlarged to permit of the necessary swinging movement of the member 45 without interference from the switch shaft 60 (Fig. 9), 105 and of such shape that the cam 43, as it slides on the upper or lower edge of this opening, may have as easy an action as possible in moving the member 45 up or down in contact with the abutment 51.

It will be noted that the cam portion 43 of the driven ratchet member 39 extends through one of the arms 65 of the switch arm 35. This necessitates an enlarged opening in this part of the switch arm, and this enlarged opening requires the provision of a correspondingly large bearing member 66 (Fig. 13) which is mounted on the switch shaft or spindle, and fits snugly in the enlarged opening in the switch arm 35. In 120 order to provide clearance for the cam 43, this enlarged bearing member 66 is cut away as indicated at 67 so that the cam can extend through it (Fig. 9). The switch frame 48 may be secured to the insulating base 20 by means of a screw 68 (Figs. 6 and 9).

As previously stated, the coil torsion

spring 49 serves to return the pull chain 36 after it has been pulled down and released; one end of this coil torsion spring being secured to a lug 69 struck up from the bearing member 63 (Figs. 6 and 10) the other end of the spring being suitably secured to the disc 58 which is clamped onto the chain rail 56.

The operation of the switch mechanism is as follows: Assuming that the switch mechanism is in the position shown in full lines in Fig. 9, which is the "on" position of the switch, and it is desired to turn the switch "off" the pull chain 36 is pulled down, and released. The pulling down of the chain moves the driving ratchet member 40 through 180 degrees, this driving ratchet member 40 being connected to move with the chain rail 56 as previously described. This movement of the driving ratchet member through 180 degrees also moves the driven ratchet member 39 through 180 degrees by engagement of the ratchet teeth 42 with the wings 41 of the driven ratchet member. As the driven ratchet member 39 is moved through this movement of 180 degrees, the cam 43 engages the upper edge of the elongated opening 44 of the swinging member 45 and raises the inner end of the latter, the rounded end 50 of this member sliding on the stationary abutment 51. When the end 50 has passed the dead center, that is, a line through the axis of the spindle 60 and the point of pressure of the spring 54 on the switch arm 35, the power stored in the spring will cause the pivoted switch arm 35 to snap to the dotted line position shown, which is the "off" position of the switch. The circuit is thus suddenly broken at two points, between the switch arm 35 and the two contacts 29 and 30 respectively.

During the return movement of the pull chain 36 and the driving ratchet member 40 under the action of the torsion spring 49, the driven ratchet member 39 remains stationary due to the fact that the retaining portion 46 of the driven ratchet member has snapped into the rectangular depression 47 in the switch frame 48.

On the next pull down of the pull chain, the switch mechanism will be snapped to "on" position, substantially as described in connection with this movement to "off" position.

What I claim as new and desire to secure by Letters Patent of the United States is:

1. A pull switch comprising a switch frame, a stationary abutment on said frame, a pivoted switch arm, and means for oscillating said switch arm back and forth comprising a swinging member engaging said switch arm and said abutment, a spring between said switch arm and said member, and means for sliding said member on said abutment to carry said spring back and forth past the axis of oscillation of said switch arm, said means comprising a rotatably mounted ratchet member and an oscillating ratchet member. 70

2. A pull switch comprising a frame, a stationary abutment on said frame, a pivoted switch arm, a member slideable in said switch arm and arranged to slide on said abutment, a spring carried by said member and bearing on said switch arm, and means for sliding said member on said abutment comprising a rotatable ratchet member and an oscillating ratchet member. 75

3. A pull switch comprising a switch frame, a stationary abutment on said frame, a pivoted switch arm oscillatable back and forth, and means for oscillating said switch arm comprising a swinging member engaging said pivoted switch arm and said abutment, and having a slot therein, a spring between said switch arm and said member, and means for sliding said member on said abutment to carry said spring back and forth past the axis of oscillation of said switch arm, said means comprising a cam working in said slot. 80

4. A pull switch mechanism comprising a ratchet mechanism including a rotatable ratchet member and an oscillating ratchet member adjacent said rotatable member for operating it, a switch arm oscillatable in a plane parallel to the plane of the rotatable ratchet member, transmission means from said rotatable member to said oscillatable switch arm whereby rotation of said rotatable ratchet member causes said switch arm to oscillate and a spring for returning said oscillatable member, said returning spring and switch arm being on opposite sides of said rotatable ratchet member. 100

In witness whereof, I have hereunto subscribed my name.

REUBEN B. BENJAMIN.
